E. A. WILKINSON

COMBINED REFRIGERATOR AND DISPLAY COUNTER

Filed August 3, 1925

Patented Jan. 26, 1926.

1,570,811

UNITED STATES PATENT OFFICE.

ELZA A. WILKINSON, OF SAN FRANCISCO, CALIFORNIA.

COMBINED REFRIGERATOR AND DISPLAY COUNTER.

Application filed August 3, 1925. Serial No. 47,915.

To all whom it may concern:

Be it known that I, ELZA A. WILKINSON, a citizen of the United States, and a resident of San Francisco, in the county of 5 San Francisco and State of California, have invented a new and useful Combined Refrigerator and Display Counter, of which the following is a specification.

The present invention relates to improvements in combined refrigerators and display counters for use in retail stores in connection with the display and preservation of meats, etc. The general object of the invention is to adapt a combined refrigerator and display counter to function both as a medium of display and as a storage place for relatively large cuts of meat. By combining the storage feature of the present invention with a display counter, the counter attendant is enabled to obtain replenishments for the stock on display from the storage space of the counter and thereby avoid the delay which has heretofore resulted in making trips from the counter to the well known form of storage box usually located in a remote portion of the establishment.

The above and other objects are accomplished by instrumentalities pointed out in the following specification.

30 The invention is clearly defined in the claims.

A satisfactory embodiment of the invention is illustrated in the accompanying drawings forming part of the specification and in which:

Figure 1 is a vertical longitudinal section of the complete invention;

Figure 2 is a vertical cross section taken on the line 2—2 of Figure 1 and on a slightly 40 enlarged scale; and

Figure 3 is a vertical cross section on the line 3—3 of Figure 1, wherein the contents is removed from the storage compartment.

In carrying out the present invention, I 45 provide a cabinet or counter *a* of conventional contour and modify this element in certain exterior and interior details of construction so as to conform with my invention.

50 The cabinet *a* has the usual insulated bottom 5, side walls 6 and 7, end walls 8 and 9, and top 10. To adapt the cabinet to function as a refrigerator, the front side wall 6 is by preference constructed with a lower imperforate area extending for the length of the wall and indicated by 11, and

the upper portion of the said side wall 6 is constructed as a frame in which are set several transparent plates 12 of glass so as to afford a view of the interior of the casing, the plates being arranged in spaced relation one behind the other so as to provide the conventional insulating air pockets.

55 The top 10 is constructed as a frame and has an internal continuous rabbet 13. The top frame receives the top plate 14 which is rabbeted to interfit with the rabbet 13 and is removably secured to the top frame by the screws 15. The top plate is also constructed as a frame and has fitted therein 70 transparencies in the form of plates of glass 16 through which the interior of the cabinet may be observed. By having the top plate removably secured, ready access to the interior of the cabinet for the purpose of 75 introducing, removing or inspecting the refrigerating apparatus (hereinafter to be described) is had.

The upper and lower portions of the inner side wall 7 are formed each with a plurality of door frames for the reception of a plurality of lower doors 17 and upper doors 18. These several doors are by preference connected to the cabinet by hinges, and close the openings in which they are arranged, the said openings being provided for giving access to the upper and lower portions of the cabinet.

80 The interior of the cabinet is divided into an upper or display compartment 19 and a lower or storage compartment 20. The division wall between these compartments is indicated generally by *b* and extends in the direction of the length of the cabinet and is disposed at the middle portion thereof. This division wall is constructed so that its opposite sides are connected to the opposite side walls 6 and 7 of the cabinet, but its end walls are spaced from the adjacent end walls 8 and 9 of the cabinet so as to 95 provide passages 21 and 22 which place the compartments 19 and 20 in communication with one another at their opposite ends.

100 The division wall *b* includes in its construction a refrigerating unit consisting of 105 an oblong, flat relatively shallow metallic casing 23 in which is disposed a refrigerating coil 24 which has extensions, one of which is shown and indicated by 25, directed through the end wall 9 and operatively connected to a refrigerating apparatus which 110 operates to circulate refrigerating fluid

through the coil. The unit 23 is horizontally disposed within the cabinet or counter and is arranged above a drip pan 26 which has upstanding flanges 27 providing supporting sills for the opposite end portions of the unit 23. The opposite side portions of the drip pan 26 bear upon ledges 28 longitudinally disposed on the inner faces of the side walls 6 and 7. The drip pan slopes downwardly from the passage 21 to the passage 22 and terminates in a gutter 29 provided with an outlet pipe 30 which is directed into an outlet 31 in the bottom 5 of the counter.

15 A display tray comprising a body 32 of foraminous material is disposed above the refrigerating unit 23 and by preference is arranged so as to slope upwardly and rearwardly from the front side wall 6, in which 20 position it is supported by longitudinally disposed ledges 33 on the opposite inner faces of the side walls 6 and 7. The display tray 32 is adapted to form a support for the material to be displayed, which in practice is usually arranged upon dishes or their equivalents 34, and the tray is so disposed with relation to the transparencies 12 and 18 of the side walls as to permit observation of its entire contents.

30 In addition to the communication between the compartments 19 and 20 afforded by the passages 21 and 22, further communication is effected through a series of ducts in the form of tubes 35 which are arranged for 35 spaced distances apart and extend downwardly through the middle portions of the casing 23 and through the corresponding portion of the drip pan 26. The upper ends of the tubes are flanged as indicated by 36 40 in Figure 2, the tubes being removably fitted in the openings of the casing and pan, as shown, and supported by the flanges 36.

A transversely disposed bridge wall or baffle 37 extends upwardly from one end of 45 the drip pan 26 remote from the gutter 29. This baffle extends across the space between the side walls 6 and 7 and forms one side of the passage 21, and its upper end extends above the display tray 32 and adjacent to the 50 top 10, the intervening space between the baffle and the top forming a continuation of the passage 21.

In the use of the device, small cuts of 55 meats such as steaks, chops, or other perishable material for filling small orders, are arranged for display in the receptacles 34 upon the display tray 32, while the larger or market cuts are disposed within the lower compartment 20, where their presence is hidden by the walls of the counter. When the 60 refrigerating unit is rendered active by circulation of refrigerant through the coil thereof, the air in the lower compartment is first chilled and moves downwardly. This 65 establishes a circulation of air through the

upper and lower compartments. The air in the upper compartment, as the same is chilled, passes downwardly through the tubes 35 and downwardly to the right of the baffle 37 and over the upper and lower faces 70 of the casing 23. The air in circulating over the lower face of casing 23 moves faster than the air on the upper side, and the motion of the lower air is accelerated by the downwardly sloped passage resulting from 75 the sloping of the drip pan; and due to this difference in the rate of circulation in different portions of the interior of the counter, the entire body of air within the counter is constantly and rapidly circulated 80 with the result that low temperatures are quickly had and readily maintained throughout the interior of the counter.

In instances where conditions might require the provision of mechanical means as 85 an auxiliary for effecting circulation within the counter, a fan blower 38 may be provided and arranged within one end portion of the lower space 20, preferably at the lower end of the passage 22, as shown in Figure 1.

90 From the foregoing it is to be observed that when the counter of the present invention is in use, the cool air is permitted to circulate entirely around the material disposed within the counter, in that the foraminous body 32 offers no impediment to circulation in connection with the display shelf, and another layer of foraminous material 39 arranged upon the upper face of the bottom 5 permits of circulation of the cold air around the material arranged thereon. Condensation forming upon the surface of the receptacles 34 or upon the casing 23 and falling therefrom is intercepted by the drip pan 26 and conveyed to the outlet 31.

100 Although I have shown and described one embodiment of my invention, it is to be understood that the same is susceptible of various changes; and I reserve the right to employ such as may come within the scope 105 of the appended claims.

I claim:

110 1. A combined refrigerator and display counter comprising a cabinet interiorly provided with an upper compartment for receiving the material to be displayed, a lower compartment for receiving the material to be stored and vertically extending passages at the opposite ends of the compartments for placing the compartments in communication with one another, a division wall between said compartments extending longitudinally and transversely of the central portion of the cabinet from one of said passages to the other and including a refrigerating unit, and means for circulating air from one of said compartments into the other and through the said passages.

115 2. A combined refrigerator and display counter comprising a cabinet having oppo-

site side and end walls, a division wall centrally located within the cabinet and extending from a point adjacent to one of the end walls thereof to a point adjacent the opposite end wall whereby end passages are provided, and upper and lower compartments, said division wall including a tray having a foraminous base portion for supporting the material to be displayed, a refrigerating unit located below and in spaced relation to the tray, a drip pan inclining downwardly from one end of the lower side of the refrigerating unit, and a baffle plate located at the higher end of the drip pan in one of said passages and extending upwardly in spaced relation to the tray beyond the space between the refrigerating unit and the tray for deflecting currents of air upon the downwardly inclined surface of the drip pan and into the space between the refrigerating unit and the tray.

3. A combined refrigerator and display counter comprising a cabinet having opposite side and end walls, a division wall centrally located within the cabinet and extending from a point adjacent to one of the end walls thereof to a point adjacent the opposite end wall whereby end passages are provided, and upper and lower compartments, said division wall including a tray having a foraminous base portion for supporting the material to be displayed, a refrigerating unit located below and in spaced relation to the tray, a drip pan located below and in spaced relation to the refrigerating unit, and a plurality of open ended tubular sections extending through the drip pan and the refrigerating unit and into the space between the tray and the drip pan and into the lower compartment. 25 30 35

ELZA A. WILKINSON.
